UNITED STATES PATENT OFFICE.

ELMER EVERET TAYLOR, OF LOOGOOTEE, INDIANA.

SOUND CONCENTRATOR FOR TELEPHONE TRANSMITTERS.

1,377,940.

Specification of Letters Patent. Patented May 10, 1921.

Application filed September 23, 1919. Serial No. 325,709.

To all whom it may concern:

Be it known that I, ELMER EVERET TAYLOR, a citizen of the United States, residing at Loogootee, in the county of Martin and 5 State of Indiana, have invented a new and useful Sound Concentrator for Telephone Transmitters, of which the following is a specification.

This invention has reference to sound concentrators for telephone instruments and is 10 designed more particularly as an attachment for transmitters used in connection with instruments adapted particularly for the deaf.

Instruments of the telephone type for aiding 15 the deaf to hear better usually comprise a telephone transmitter and a telephone receiver, together with a source of current such as a small battery, and connections whereby the whole instrument is individual 20 to the deaf person, the battery and transmitter being carried on the person in convenient position to be reached by sound waves and the receiver being at one end of a flexible cord connected at the other end to 25 the transmitter so that the receiver may be conveniently placed at the ear of the wearer. Such instruments are, however, subject to distracting influences but such distracting conditions are eliminated by the invention 30 which comprises a cap to fit snugly over the sound receiving mouthpiece of the transmitter. The cap has a face portion with a sound transmitting opening therein similar in exterior contour to an ordinary transmitter mouthpiece but of a depth to space the 35 sound receiving opening a suitable distance from the mouthpiece of the transmitter to which the cap is applied. The interior of the cap is provided with a concentrating 40 cavity of a nature to direct sound which might otherwise confuse the impingement of the received sound onto the diaphragm of the transmitter so that such formerly confusing sounds are all reflected and diverted 45 directly onto that portion of the transmitter diaphragm most susceptible to the received sounds. The result is that the received sound is clarified and so made more distinct and is also concentrated onto the 50 central portion of the transmitter diaphragm in such manner as to greatly amplify or magnify the received sound, with the further result that the reception of the sound is made clearer and more intense than has heretofore been the case.

The invention will be best understood

from a consideration of the following detailed description taken in connection with the accompanying drawing forming part of this specification, with the understanding, 60 however, that the invention is not confined to any strict conformity with the showing of the drawing, but may be changed and modified so long as such changes and modifications mark no material departure from 65 the salient features of the invention as expressed in the appended claims.

In the drawing:

Figure 1 is a perspective view of a form of local telephone for use by a deaf person, 70 with the invention applied.

Fig. 2 is a side elevation of the transmitter with some parts in section.

Fig. 3 is an elevation of the sound concentrator as viewed from the rear face. 75

Referring to the drawing, there is shown a telephone transmitter 1 which may be of any suitable type such as is adapted for use in connection with instruments for aiding hearing by the deaf. The transmitter 80 is mounted upon a suitable battery 2, of which only the casing is shown in the drawing, for neither the interior construction of the transmitter nor the interior construction of the battery is illustrated in the drawing, 85 these parts following the usual custom and in their details forming no part of the invention. The transmitter 1 has a mouthpiece portion 3 with a ledge 4 and shoulder 5 about its periphery, the construction of 90 these parts being such as is customarily employed and therefore requiring no particular description. The transmitter 1 is provided with a loop 6, whereby the transmitter with the battery 2 may be fastened to the 95 clothing of the wearer, preferably in front of the chest as a convenient location for receiving sound waves from a person talking to the wearer of the transmitter. Fast to the transmitter is one end of a flexible 100 cord 7, the other end of which is attached to a telephone receiver 8 adapted to be placed against the ear of the user. The receiver 8 is provided with suitable switch mechanism of which a manipulating finger-piece 9 only is shown, for the switch may be of known construction and requires no special description, nor need its specific construction be indicated in the drawing for an understanding of the invention. The 105 finger-piece 9 is moved in one direction to couple up the battery, transmitter and re-

ceiver for listening purposes, and is moved in the other direction to cut out the battery when the instrument is not in use.

The instrument so far described is of commercial form and is found upon the market and is especially adapted for the application of the invention without any change whatever or necessitating the use of tools or the modification of the invention or instrument.

10 The invention is best shown in Figs. 2 and 3 which illustrate sectional and interior views respectively, while the exterior configuration of the invention best appears in Fig. 1.

15 The invention comprises a cap 10 of open cylindrical form at one end as shown at 11, and terminating in a circumferential flange 12 shaped to snugly fit over the ledge 4.

From the flange 12 the exterior of the cap 20 10 is frusto-conical as shown at 13, the exterior wall being ultimately returned upon itself and toward the flange 12 with the return portion approaching the longitudinal axis of the cap to provide an inturned conical mouthpiece or duct 14 with a central opening or passage 15 for sound waves, the passage 15 providing for the entrance of the sound waves into the interior of the cap 10. The mouthpiece 3 of the transmitter bulges 25 outwardly from the shoulder 5 for a short distance and that wall of the cap 10 toward the flange 12 is thickened to provide a cylindrical inner wall 16 of an axial depth approaching about half, or a little more, of 30 the full depth of the interior of the cap 10, where the cap when applied to the transmitter mouthpiece defines a cavity 17.

From the outer margin of the wall 16 the interior of the cap is formed with a conical 40 wall 18 receding from the flange 12 and wall 16 to about half the distance between the wall 16 and the mouthpiece opening 15 and from such point the cavity 17 is formed with another wall 19 of conical form approaching the mouthpiece of the transmitter and the longitudinal central axis of the cap until it reaches the opening 15. The cavity 17 therefore is in the main of cylindrical conformation with a portion immediately 50 underriding or back of the sound-receiving face of the cap of reversely conical shape with the small end of the outer conical wall and the large end of the inner conical wall merging and there defining the point of 55 greatest distance of the cavity 17 from the mouthpiece of the transmitter.

The result of such construction is that sound waves reaching the transmitter are directed through the opening 15 into the cavity 17 directly toward the regular sound-receiving diaphragm of the transmitter. Ordinarily but a relatively small part of the sound waves is caught by such diaphragm and by far the larger portion is lost. With 65 the cap 10 in place all the sound waves en-

tering through the passage 15 either directly reach the transmitter diaphragm or are reflected by the walls 16, 18 and 19 in paths causing the sound waves to ultimately strike the diaphragm of the transmitter. The 70 quantity of sound waves so becoming effective include all or nearly all the energy represented by the originally projected sound waves and the intensity of the received sound and the energy transmitted to the telephone receiver at the ear of the hearer is greatly increased. Because of this the user is enabled to plainly hear the transmitted sounds because of their loudness while the direction of reflection or transmission of the 75 sounds in the cavity or chamber 17 prevents interference of these sounds and hence a clarity of the received sound greatly exceeding the usual reception of sound where the sound appears weak to the deaf person and 80 there is loss of clearness due to the interference of cross waves of sound caused by obstructing reflections of the sound in the usual forms of amplifiers.

The angular relation of the walls 18 and 90 19 to each other and to the cylindrical wall 16, and also their relation to the transmitter diaphragm, are important as affecting the clearness and intensity of the sounds reaching the ear of the listener. 95

The walls 18 and 19 join at an obtuse angle to each other and the wall 18 joins the wall 16 at an obtuse angle and as the walls are circular the sound waves reaching them are reflected toward the central part of the 100 transmitter diaphragm.

The frictional fit of the cap 10 on the head of the transmitter permits the ready application or removal of the cap and the fitting of the cap to heads varying somewhat in size. 105

The instrument shown in the drawing, with the exception of the attachment shown separately in Fig. 3, is the device for aiding the deaf to hear, known upon the market as the ear-phone, and it is for such instrument 110 that the invention is particularly designed and for which it is particularly adapted.

The instrument referred to employs a telephone transmitter to which the attachment of the invention is applied, and a telephone 115 receiver to be held to the ear of the user. As the invention is useful for both the instrument for aiding the deaf to hear and the usual commercial telephone, the term telephone transmitter has been used in the description and claims as generic enough to apply to such and to other acoustical instruments.

What is claimed is:—

1. A telephone instrument provided with 125 a source of electric energy, a microphonic telephone transmitter carried thereby, a telephone receiver connected to the transmitter, and a sound clarifying and amplifying cap adapted to fit snugly over the sound receiv- 130

ing mouth-piece of the transmitter and producing a cavity in conjunction therewith, with a concentrating mouth-piece directed toward the transmitter diaphragm and 5 shaped to form an inturned conical mouth-piece opening into a doubly conical cavity receding from the transmitter diaphragm and then approaching the diaphragm with the walls shaped to accumulate and direct 10 the reflections of sound against the central portion of the transmitter diaphragm.

2. A sound concentrator for telephone instruments, comprising a cap for the mouth-piece end of the transmitter having a central sound transmitting opening over and approximately of the same size as that of the transmitter to snugly embrace the transmitter casing, with the depth of the cap such as to space the sound receiving face of 15 the cap away from the transmitter by about approximately half the full depth of the cap and said cap having an interior cylindrical wall surrounding the transmitter mouth-piece with the outer end of the cap provided 20 with frusto conical inner walls meeting intermediately between the cylindrical wall and there merging, whereby the inner walls 25 of the cap constitute reflecting surfaces for

sound waves directing said waves toward and concentrating them onto the central portion of the receiver diaphragm. 30

3. In a sound concentrator for telephone transmitters and other similar acoustical instruments, a cap for application to the sound receiving head of the instrument and having 35 the head of the cap remote from that applied to the instrument provided with an opening for the admission of sound, with the size of the cap related to the size of the head of the instrument to form a cavity of substantially 40 the diameter of the sound receiving head of the instrument and of a depth to provide a chamber, with said chamber having cylindrical side walls and end wall in which the sound receiving opening is located and said 45 end of the head between the cylindrical side walls and the outer end of the head having obtusely joined conical walls facing toward the head of the instrument with the outer conical wall extending from the sound receiving opening at the outer end of the cap. 50

In testimony that I claim the foregoing as my own, I have hereto affixed my signature.

ELMER EVERET TAYLOR.
